UNITED STATES PATENT OFFICE.

JAMES S. ARCUS, OF CHICAGO, ILLINOIS.

CASHIER'S TICKET.

1,276,159.

Specification of Letters Patent. Patented Aug. 20, 1918.

Application filed January 29, 1915. Serial No. 5,056.

To all whom it may concern:

Be it known that I, JAMES S. ARCUS, a citizen of the United States, residing at Chicago, in the county of Cook and State of Illinois, have invented certain new and useful Improvements in Cashiers' Tickets, of which the following is a specification.

This invention relates to tickets, and particularly to meal tickets or checks of a kind adapted for use in restaurants, and the like.

It is now common practice in lunch rooms to employ tickets having one or more rows of numerals printed thereon, corresponding to the various prices which may be charged a customer for his meal. Each waiter carries a supply of these printed tickets, and after serving the customer gives him a ticket which is punched or cut through or adjacent to the proper number to indicate the amount of the bill to be paid to the cashier. This system necessitates, of course, that each waiter carry a punch, or other instrument, for punching holes through or cutting the tickets in such a manner that they will have a significant indication for the customer and the cashier, and such use of punches or cutting devices not only inconveniences and annoys the waiters, but also involves considerable loss of time and expense to the management.

The principal object of my invention is to provide a ticket having a series of numerals or other indicia printed thereon, which may be carried by waiters or other persons, and which may be manipulated to provide a significant and particular indication for the customer or cashier without the necessity of using a punch or other instrument. A further object is to provide a ticket of the kind referred to which may be altered to furnish a significant indication without detaching any of the said numerals or indicia from the body of the ticket.

More specifically, the invention comprises a ticket having a series of numerals printed thereon, and a plurality of detachable portions, one of which is located adjacent each of said numerals, said detachable portions being capable of being readily detached by the hands of the user to provide the proper significant indication.

Other features and objects of the invention will be set forth more specifically in the following specification and accompanying drawings, in which—

Figure 1 shows a plan view of a ticket

embodying the features of my invention; and

Fig. 2 shows a plan view of another ticket showing an extension of the features of my invention.

Referring to the drawings, the ticket 10, which is formed of cardboard or the like, has printed thereon a series of numerals, as shown, varying in this instance from 5 up to 60 by steps of 5; and these numerals are preferably arranged in two rows, 12 and 13, spaced inwardly somewhat from the longitudinal edges 14 and 15 of the ticket. These numerals should preferably be printed in 65 rather large type, and by arranging them as shown a comparatively large range of numerals may be printed on the ticket without unduly increasing the size thereof. At the head of the ticket I preferably print the 70 number of the ticket, as shown at 16, in order that the number of tickets used may be ascertained at any time, and also in order that the number of customers served may be determined in those instances where a single 75 ticket is given to each customer.

Located preferably beneath the number of the ticket, as at 17, the legend "Pay cashier highest amount indicated" is printed on the ticket for the information of the customer, 80 and, as will be seen from the drawings, the series of numerals 11 corresponding to the different prices which may be paid to the cashier, are arranged below the legend 17. Other information or advertising matter 85 may be printed on the ticket between the two rows of numerals 12 and 13, as shown at 18.

The ticket is provided, opposite each of the numerals 11, and between said numerals 90 and the adjacent edges 14 and 15 of the ticket, with a pair of inclined slits 19. These slits extend completely through the body of the ticket and converge inwardly from points 20, adjacent the edge of the ticket, 95 toward the adjacent one of the numerals 11 printed on the ticket. The slits 19 do not intersect, however, but terminate at their inner extremities short of the point of their convergence if they were extended. By this 100 construction it will be seen that a series of tabs or detachable portions 21 are formed, each of which is attached to the body of the ticket at three points, 22, 23, and 24. The tabs 21 are thus firmly attached to the body 105 of the ticket, and at the same time they may be readily detached therefrom by the user,

who grips the proper tab 21 between his fingers and severs the connection of said tab from the body of the ticket at the points 22, 23, and 24. The triangular shape of the tab, 5 together with the construction whereby the tab is attached at three points only, permits of this ready detachment of the tab, and at the same time all of said tabs are so firmly secured to the body of the ticket as to render 10 very improbable the possibility of their becoming accidentally detached therefrom. The inclined slits 19 of each pair of such slits are so located as to converge toward the central portion of the adjacent numeral, 15 so that the resulting aperture 21^a, formed by the detachment of one of said tabs, will be directed toward the adjacent numeral, so as to give a clear indication to the customer of the amount to be paid the cashier.

20 In Fig. 2 I have shown a ticket 10^a which is in all respects substantially similar to the ticket 10, except that the legend 17^a reads "Pay cashier amount indicated" and along the bottom of the card, and spaced inwardly 25 from the bottom edge 26, there is provided a series of numerals 27 which indicate the amount to be paid to the cashier in dollars, or other large denominations, as desired. The other numerals shown adjacent to the 30 vertical edges of the ticket indicate the amount to be paid the cashier in cents, or other small denominations, and the combination of these numerals with the row of numerals along the bottom edge of the ticket 35 makes it possible to use a single ticket for indicating the amount to be paid for a large purchase of goods, or by a party of several persons. As shown in Fig. 2, inclined slits 19^a are provided opposite each of the vertical 40 rows of numerals; and similar inclined slits 19^b are also provided opposite each of the lower horizontal rows of numerals, so as to form detachable tabs 21^b opposite each numeral of the row of numerals 27. It will 45 be apparent that this form of ticket should preferably be given the customer with the proper tabs detached after the purchase or transaction has been fully completed, the amount to be paid the cashier being the sum 50 of the amounts indicated by the detached tabs in the dollars and cents.

The inclined slits 19, 19^a, and 19^b, above described, extend completely through the body of the ticket and are continuous from 55 end to end, but are not extended to the point of their intersection, so that a detachable tab is formed which is attached to the body of the ticket at each end of each slit. If desired, the slits may be extended so as to intersect and form a continuous slit 19^c, as 60 shown in Fig. 2, the resulting detachable tab being attached to the body of the ticket only at the points 28 adjacent the edge of the ticket at each end of the slit 19^c.

65 From the foregoing description it will be

apparent that I have provided a form of ticket which may be carried in any number by a waiter or other person, and which may be manipulated conveniently by the fingers of the user in order to detach one of the tabs 70 and provide a significant indication for the customer and cashier. It will be understood, however, that I have shown a specific form of my invention for purposes of illustration, and that it may be embodied in various 75 other forms and adaptations, and used in other locations than lunch rooms, without departing from the spirit of the invention as defined by the appended claims.

I claim:—

1. A cashier's ticket of substantially rectangular form having a row of numerals printed thereon parallel to and spaced inwardly from an edge of said ticket, with a plurality of substantially triangular detachable tabs formed on said ticket, one located adjacent each of said numerals, said tabs being separated from the body of the ticket by slits extending through the body of the ticket, a portion of the latter extending between adjacent tabs, said tabs being united to the body of the ticket at the ends of said slits, and being located with their bases at said edge of said ticket and capable of being detached by being gripped between the fingers of the user.

2. A cashier's ticket of substantially rectangular form having a row of numerals printed thereon parallel to and spaced inwardly from an edge of said ticket, a plurality of substantially triangular detachable tabs formed from the body of the ticket and located between said edge and said numerals, one of said tabs being located adjacent each of said numerals, said tabs being separated from the body of the ticket by slits extending through the body of the ticket, a portion of the latter extending between adjacent tabs, said tabs being united to the ticket at each end of each of said slits, and being located with their bases at said edge of said ticket whereby the removal of one of said tabs by the fingers of the user will leave an indentation pointing toward one of said numerals.

3. A cashier's ticket of substantially rectangular form having a row of numerals printed thereon parallel to an edge of said ticket, with a plurality of detachable tabs formed from the body of said ticket, one of said tabs being provided for each of said numerals, said tabs being separated from the body of the ticket by slits extending through the body of the ticket, one of said slits extending along each of the inner edges of said tabs whereby said tabs are united to the body of the ticket only at their corners, a portion of the body of the ticket extending between adjacent tabs, said tabs being located adjacent said edge of said

ticket whereby they may be detached by being gripped between the fingers of the user.

4. A cashier's ticket having a row of numerals printed thereon parallel to an edge 5 of the ticket, with a plurality of detachable tabs formed from the body of said ticket, one of said tabs being provided for each of said numerals, a portion of the body of the ticket extending between adjacent tabs, said 10 tabs being separated from the body of the ticket by apertures through the ticket.

5. A cashier's ticket having a row of numerals printed thereon parallel to an edge of the ticket, with a plurality of substan-

tially triangular detachable tabs formed 15 from the body of said ticket, one of said tabs being provided for each of said numerals, a portion of the body of the ticket extending between adjacent tabs, said tabs being separated from the body of the ticket 20 by apertures through the ticket.

In testimony whereof, I have subscribed my name.

JAMES S. ARCUS.
